UNITED STATES PATENT OFFICE.

ADOLPH ROSNER, OF BRIDGEPORT, CONNECTICUT, ASSIGNOR TO THE LOCOMOBILE COMPANY OF AMERICA, OF BRIDGEPORT, CONNECTICUT, A CORPORATION OF WEST VIRGINIA.

WIND-SHIELD.

1,248,921.

Specification of Letters Patent. Patented Dec. 4, 1917.

Application filed September 2, 1914. Serial No. 859,731.

To all whom it may concern:

Be it known that I, ADOLPH ROSNER, a subject of the Emperor of Austria-Hungary, and a resident of Bridgeport, county 5 of Fairfield, State of Connecticut, have invented an Improvement in Wind-Shields, of which the following description, in connection with the accompanying drawings, is a specification, like characters on the 10 drawings representing like parts.

This invention relates to wind shields and more particularly, though not exclusively, to wind shields intended for use on automobiles.

15 The invention will be best understood by reference to the following description when taken, in connection with the accompanying illustration of one specific embodiment thereof, while its scope will be more particularly pointed out in the appended claims.

In the drawings,

Figure 1 is a front elevation of a wind shield embodying one form of the invention; and

25 Fig. 2 is a side elevation of the wind shield shown in Fig. 1, the same being illustrated as applied to the body of an automobile.

Referring to the drawings and to the embodiment of the invention therein shown for 30 illustrative purposes, I have represented at 1 what may be considered a portion of a typical automobile body illustrative of devices of that class. At 2 is represented a 35 bonnet covering the engines and at 3 a dash board on top of which is fixedly secured in an upright position a wind shield frame. This comprises a lower portion 4 shaped to conform to the contour of the dash board 3 40 and snugly fitting the top thereof. Secured to the top of the base 4 is a semi-rectangular frame 5 in which there is held a lower panel 6 preferably of glass or some other transparent material. The upper ends of the 45 sides of the rectangular frame are provided with hubs 7 on which are pivotally and adjustably clamped the upright supports 8 for the upper panel of the wind shield. The upright supports 8 at their upper ends 50 carry between them the transverse panel supporting rod 9 having threaded ends provided with adjustable knots so that the rod can be clamped tightly between the end supports 8 by means of thumb knots 10.

55 Swiveled upon the transverse rod 9 are a

pair of L shaped frames 11, each one carrying a section 12 of the upper panel, these sections being also preferably of glass or some other transparent material. The upper panel is thus composed of a plurality of 60 sections, and in virtue of the swivel support on the transverse rod 9 each section may be independently adjusted and moved to any desired inclination such as is shown assumed by the left hand panel section in Fig. 1. 65 The rain vision can thus be opened in front of the operator while closed in front of the other occupant of the forward part of the car. The swivel connections of the upright supports 8 to the lower frame 5 permit the 70 entire upper panel section also to be adjustably inclined as required, said upper panel section being clamped in position by any suitable means such as the knots 13 provided with the hand levers as shown. 75

In order to provide that the water when it rains will tend to run toward the edges of the panel, thereby to be deflected from a position where it can blow or come in through the opening against the occupants of the vehicle, the lower edge of the upper panel or of each section thereof where the upper panel is sub-divided, is inclined downwardly toward the outer lower corners from the inner lower edges of the panel, so that 80 the rain in following the lowest point of the wind shield will drip off the lower edges thereof. As indicated in Fig. 1, the lower edge of each upper panel section is curved 85 and concave in form so that the outer lower corners are at a lower point than the lower central portion of the panel, and the outer edge of each section is at a lower point than any other point along the lower edge of that section. To fit the concave lower edge of 90 the upper panel portion the upper edge of the lower panel section is made convex in form. 95

The base of the wind shield may be, and 100 preferably is, provided with a wall 14 hinged along the lower edge of the frame 5 and so arranged that it may be swung forwardly to open a ventilating space thereat and ventilate the space behind the lower panel of the wind shield. 105

While I have herein shown and described for purposes of illustration one specific form of the invention, it is to be understood that extensive deviations may be made therefrom without departing from the spirit thereof. 110

Claims:

1. In a windshield the combination with a lower glass having a convex upper edge and an upper glass movable with reference to said lower glass and having a concave water-shedding lower edge, whereby rain drops falling on said upper glass may run to the extreme lower edge thereof and thence pass along said concave lower edge.
- 5 to the side of the windshield under the combined action of gravity, adhesion and cohesion.
2. In a windshield the combination with a frame having a lower glass with a convex upper edge and an upper glass movable with reference to the lower glass and having a concave water-shedding lower edge to fit the convex edge of the lower glass, said concave edge serving to deflect rain drops to
- 15 the side of the windshield while providing a substantially unobstructed vision.
3. The combination with an automobile body of a shield for protecting the occupants thereof, a lower panel having an upper convex edge, an upper panel having a lower concave edge, said upper panel being composed of a pair of sections and a frame
- 20
- 25

whereon said upper panel sections may be independently adjusted for different inclinations.

4. In a windshield the combination with a lower glass having a convex upper edge and an upper glass movable with reference to said lower glass and having a concave lower edge, said upper glass being composed of a plurality of separately movable sections whereby rain drops falling on said upper glass may run to the extreme lower edge thereof and thence pass along said concave lower edge to the side of the windshield under the combined action of gravity adhesion and cohesion.

5. In an automobile, a windshield having a lower glass 6 having a convex upper edge, and the upper adjustable glass 12—12 having a lower concave edge extending the full width of the windshield.

In testimony whereof, I have signed my name to this specification in the presence of two subscribing witnesses.

ADOLPH ROSNER.
